VARIABLE INDUCTIVE COUPLER

Ivan Keith Munson, Forrest Heights, Md.

Application October 25, 1948, Serial No. 56,321

9 Claims. (Cl. 171—119)

(Granted under the act of March 3, 1883, as
amended April 30, 1928; 370 O. G. 757)

1

This invention relates to variable radio-frequency inductive couplers and is particularly useful in electronic circuits for coupling the balanced outputs of two tubes to the input of a single succeeding tube.

The prior art contains many devices for varying the magnetic coupling between two or more coils by varying their physical relationship in space. While these devices are generally satisfactory in operation, they involve the use of relatively complex and bulky mechanical structures. It is of the utmost importance that the component parts of a circuit handling high radio frequency currents be arranged in close physical proximity and in an electrically balanced configuration. The intimate physical relationship of the components in such a circuit precludes the use of conventional variably coupling devices and puts a premium on extremely simple and compact designs. It is therefore the general object of this invention to provide a simple and compact variable radio-frequency inductive coupler having no metallic operating parts.

It is another object to provide a variable coupling transformer having two primary coils which may be simultaneously moved to and from a stationary secondary coil, the coupling between one primary coil and the secondary coil being always equal to the coupling between the other primary and the secondary coil.

It is a further object to provide a variable coupling transformer having coils and a single member for varying the spacing of the coils.

It is a further object to provide a novel variable inductor of extremely simple construction.

In pursuance of these and other objects which will be apparent to those skilled in the art, a cylindrical rod of insulating material is provided having a circular groove on the central portion of the rod, a right-hand helical groove on one side of the central portion and a left-hand helical groove on the other side of the central portion. A secondary coil is wound in the circular groove and helical primary coils are positioned in the helical grooves. The helical coils of wire in each of the helical grooves are prevented from rotation by support means so that the helical coils may be moved axially to and from the central secondary coil by rotating the rod.

For a better understanding of the invention, reference is had to the following description taken with the accompanying drawings wherein:

Figure 1 is a top plan of one physical embodiment of the invention.

Figure 2 is a front elevation of the same.

2

Figure 3 is a schematic diagram of the invention connected for use as a variable transformer having two inputs and one output.

Figure 4 is a schematic diagram of the invention connected for use as a variable transformer having one input and one output.

Figure 5 is a schematic diagram of the invention connected for use as a variable inductor.

Figure 6 is a physical embodiment of the same, part of the rod being broken away to show a slug of poly-iron imbedded therein.

Referring now in greater detail to Figures 1 and 2 of the drawings, the variable transformer has a base plate 10 provided with mounting screw holes 11, 11 on the end portions thereof. Upright side members 12 and 13 mounted on the base plate 10 are provided with coaxial bearing apertures 14 and 15 respectively. Guide bars 16 and 17 extend between the side members 12 and 13, and are provided with longitudinal slots 18 and 19 respectively. The base and side members thus far described are preferably made of an insulating plastic material.

A cylindrical rod generally designated 20 is constructed of an insulating plastic material, such as polystyrene, characterized by having a very low dielectric loss when subjected to high frequency radio energy. The cylindrical rod 20 has end portions 21 and 22 of reduced diameter 30 which are journaled in the bearings 14 and 15 of the side members 12 and 13. The end portion 22 extending from the side member 13 is provided with a cerf 23 to permit rotation of the cylindrical rod 20 by means of a screw driver. The other end 21 of the cylindrical rod 20 is provided with a crank arm 24 for manual rotation of the cylindrical rod 20. The cerf 23 and the crank arm 24 are alternative constructions, one or the other may be provided according to the mode of operation desired.

The central portion of the rod 20 is provided with an annular groove designated 26 formed between two circular beads 27 and 28. A right helical groove 30 is provided on the surface of the cylindrical rod 20 on one side of the central annular groove 26, and a left hand helical groove 31 is provided on the other side of the central annular groove 26.

A helical coil 32 is wound to conform with the pitch and diameter of the helical groove 30. The ends 33 and 34 of the coil 32 extend through the longitudinal slot 19 in the guide bar 17. Another helical coil 35 is wound with the same pitch and diameter as the helical groove 31. The ends 36 and 37 of coil 35 also extend through the lon-

itudinal slot 19 of the guide member 17. The helical coils 32 and 35 are designed to fit snugly in the helical grooves 30 and 31 respectively and yet be loose enough to permit rotation of the cylindrical rod 20 without causing rotation of the helical coils 32 and 35. The helical coils 32 and 35 will ordinarily be employed as primary coils and will be herein so designed, but of course, the connection may be reversed so that they are employed as secondary coils.

A secondary coil 38 is provided in the central annular groove 26, the coil having leads 39 and 40 extending through the longitudinal slot 18 in the guide member 16. The secondary coil 38 is located equi-distant from the helical coils 32 and 35, is prevented from axial movement by the beads 27 and 28, and is prevented from rotation by the guide member 16. The secondary coil 38 fits loosely enough in the groove 26 to permit rotation of the cylindrical rod 20 without causing rotation of the secondary coil 38. It is apparent that the secondary coil 38 is at all times maintained in a stationary position in coaxial relationship with the helical coils 32 and 35.

In the operation of the transformer, the coupling between the helical primary coils 32 and 35 and the secondary coil 38 may be varied by rotating the cylindrical rod 20 with a screw driver or by manually turning the end crank 24. Since one of the helical grooves 30 and 31 is a right hand helix and the other is a left hand helix, turning of the cylindrical rod in one direction will cause the helical coils 32 and 35 to move toward the secondary coil 38, always maintaining an equal spaced relationship therebetween. When the cylindrical rod 20 is rotated in the opposite direction the helical coils 32 and 35 are made to move axially away from each other and away from the secondary coil 38, always maintaining a balanced spaced relationship. The axial movements of the helical coils 32 and 35 results from the action of the guide bar in preventing rotation of the helical coil. The construction employed is such that the friction between the coils and the rod 20 will maintain the coils in any spaced relationship to which they are moved. No stop or holding mechanism of any kind is required.

It is within the contemplation of this invention that the cylindrical rod 20, and the coils 32, 35 and 40 may be employed in a circuit without the base plate 10, the end bearing members 12 and 13 or the guide members 16 and 17. When so employed, the coil leads 33, 34, 36, 37, 39 and 40 will be of sufficient thickness to render the structure self supporting. The various leads will then be connected directly to the adjacent circuit elements and the cylindrical member 20 will be supported in mid air by the coil. This arrangement permits the use of very short leads and the intimate physical relationship of the various circuit elements. The various leads being directly connected to the other circuit elements which are anchored to the chassis of the equipment, the coils are prevented from rotation when the cylindrical rod 20 is rotated to vary the coupling between the coils. The cylindrical rod 20, of course, maintains the coils at the proper coaxial physical relationship.

Figures 3 and 4 illustrate two different ways of connecting the coils 32, 35 and 38. In Figure 3, the output of two balanced circuits may be connected at 43 and 42 respectively to the primary coils 32 and 35. The energy induced in the secondary coil 38 is always equally the result of the inputs at 42 and 43, regardless of the positions

of the coils 32 and 35. In Figure 4, a single input is applied to the primary coils at 44, there being a jumper 45 of flexible material connecting one side of each of the coils 32 and 35. Various other methods of utilizing the variable coupling transformer of this invention will be apparent to those skilled in the art.

Figs. 5 and 6 illustrate the use of the invention to provide a variable inductor, the inductance between the points 46 and 47 being variable by adjusting the relative position of the two coils 32 and 35. A jumper 48 of resilient material is connected between the ends of both coils. A slug of poly-iron 49 is centrally and coaxially disposed in the interior of the cylindrical rod 20. The slug of poly-iron in the center of insulating rod 20 is operative to lower the magnetic reluctance of the field and effectively increase the range over which the inductance between points 46 and 47 may be varied as the spacing of coils 32 and 35 is varied by rotating the rod 20.

It is apparent that a very simple and effective device has been provided for varying the coupling between a plurality of coils, the coils being at all times maintained in a balanced physical and electrical relationship.

While the invention has been shown and described in connection with specific embodiments, it will of course be understood that the invention is not limited thereto, since it is apparent that the principles herein disclosed are susceptible to numerous other applications, and modifications may be made without departing from the spirit and scope over the invention as set forth in the appended claims.

The invention described herein may be manufactured and used by or for the Government of the United States of America for governmental purposes without the payment of any royalties thereon or therefor.

What is claimed is:

1. A variable coupling transformer comprising a cylindrical rod of insulating material journaled for rotation, the rod having a helical groove of uniform pitch and diameter on one portion thereof and an annular groove on another portion, a helical coil of wire slidably wound in the helical groove, and a second coil of wire slidably wound in the annular groove, means for rotating the rod and support means for preventing the rotation of the coils whereby, upon rotation of said rod, the helical coil of wire is axially moved along the rod and the second coil remains in a fixed position with respect to the longitudinal axis of said rod.

2. A variable coupling transformer comprising a rod of insulating material journaled for rotation, the rod having a centrally located annular groove, and a helical groove on each side of the circular groove, a helical coil of wire wound in each of the helical grooves, a third coil of wire disposed in the annular groove, means for rotating the rod and support means for preventing rotation of the coils.

3. A variable coupling transformer comprising a rod of insulating material journaled for rotation, the rod having a right-hand helical groove on one side of its central portion and a left-hand helical groove on the other side of the central portion, a helical coil of wire wound in each of the helical grooves, a third coil of wire positioned between the helical coils, support means for preventing rotation of the coils, and means for rotating the rod.

4. A variable coupling transformer comprising

a rod of insulating material having a right-hand helical groove on one side of its central portion and a left-hand helical groove on the other side, a helical coil of wire wound in each of the helical grooves, and a third coil of wire on the central portion of the rod, the ends of the coils being adapted for connection directly to other circuit elements thereby preventing rotation of the coils about their common axis, and engageable means on the rod for rotation thereof.

5. A variable coupling transformer comprising a rod of insulating material having a centrally located annular groove, a right-hand helical groove on one side of the central groove, and a left-hand helical groove on the other side of the central groove, a secondary coil wound around the rod in the central annular groove, a helical coil of wire wound in each of the helical grooves, the ends of the coils being adapted for connection directly to other circuit elements thereby preventing rotation of the coils about their common axis, and engageable means on the rod for rotation thereof.

6. A variable inductor comprising a base, a rod of insulating material journaled on the base, the rod having a right-hand helical groove on one side of the central portion and a left-hand helical groove on the other side, a helical coil of wire wound in each of the helical grooves, and a flexible jumper connecting one end of each coil, the other ends of the coils being terminals of the inductor, whereby rotation of the rod is operative to change the inductance between the terminals.

7. The inductor defined in claim 6 wherein a slug of magnetic material is positioned coaxially within the central portion of the rod.

8. A variable inductance device comprising a rod of insulating material journaled for rotation, a right hand helical groove formed in one side of said rod and a left hand helical groove formed in the other side of said rod, a helical coil of wire wound in each of said grooves, means for rotating the rod and support means for preventing rotation of the coils.

9. The device of claim 8 wherein the pitch of said grooves are substantially equal in opposite senses.
